UNITED STATES PATENT OFFICE.

HENRY H. RIGGIN, OF WILMINGTON, DELAWARE.

DRIP-COCK FOR LOCOMOTIVE-CYLINDERS.

SPECIFICATION forming part of Letters Patent No. 410,448, dated September 3, 1889.

Application filed April 11, 1889. Serial No. 306,854. (No model.)

To all whom it may concern:

Be it known that I, HENRY H. RIGGIN, a citizen of the United States, residing at Wilmington, in the county of New Castle and 5 State of Delaware, have invented new and useful Improvements in Drip-Cocks for Locomotive Steam-Cylinders, of which the following is a specification.

My invention relates to that class of devices 10 commonly known as "waste-cocks" or "drip-cocks" for steam-cylinders, to relieve the latter of the water of condensation accumulating therein. In railway-locomotives apparatus of this character is constantly used; and it is the 15 purpose of my present invention to so organize a drip-cock that it shall not only subserve the functions indicated by its name, but shall also serve as an index to the engineer of the condition of the interior packing of the cyl- 20 inder and piston, enabling him to determine in an instant whether the packing is sound or tight or so far defective that the engine should be sent to the shops for repairs.

It is my further purpose to provide a drip- 25 cock for the steam-cylinders of locomotives having increased durability, of great simplicity, and in which the drip is removed from both ends of the cylinder simultaneously, the waste-cock being provided with two distinct 30 outlets, which are both thrown open in unison.

The invention consists to these ends in the several novel features of construction and new combinations of parts hereinafter fully set forth, and then definitely pointed out in 35 the claims following this specification.

Referring to the accompanying drawings, Figure 1 is a central horizontal section of a drip-cock and its immediate connections embodying my invention. Fig. 2 is an end elevation showing the waste-cock in place, with an actuating-lever mounted on the valve-stem and provided with a stop-pin to control the throw of the lever. Fig. 3 is a portion of a locomotive-cylinder, showing my invention 45 applied thereto.

In the said drawings, the reference-numeral 1 designates the body or valve-casing of the drip-cock, having opposite interiorly-threaded wings 2, which receive the ends of the drip- 50 pipes 3, which enter opposite ends of the steam-cylinder, respectively. The interior of the body 1 is cut away to form a valve-seat,

which is of slightly less diameter at one end than at the other, the preferred construction being one-sixteenth of an inch to an inch in 55 depth. This valve-seat terminates a little short of the end of the valve-casing 1, through which a central opening of any suitable diameter is drilled. Lying upon the valve-seat described is a valve 4 of corresponding form, 60 having at one end a stem 5, passing through the central opening in the end of the body 1, and receiving two nuts 6 and 7, the one being a draft-nut, by which the valve is held upon its seat with suitable force, and 65 the other a jam-nut to confine the former. Within the body of the valve 4, upon opposite sides of the axial line, are formed two similar passages or channels 8, which may be caused to register at one end with channels 70 9, communicating with the drip-pipes. When so placed, their other ends will register with channels leading to the outlets. These outlets consist of short nipples 10, projecting from the lower (and relatively to the locomotive the inner) end of the body 1. These nipples or outlets are arranged at an angle with the horizontal of from twenty to thirty degrees, or any other suitable angle, giving said nipples a downward and widely-diver- 75 gent line of discharge. If desired, also, these nipples may be turned slightly inward or toward the locomotive. Upon the inner end of valve 4 is rigidly mounted a depending lever 12, which may be operated from the cab of 80 the locomotive by any suitable means. Projecting from the outer face of this lever is a stop-pin 13, which runs, as the lever swings back and forth, in a segmental recess 14, cut in the lower face and at the outer end of the 85 valve-casing 1. At each end of this recess is a shoulder 15, with which the stop-pin makes contact to limit the throw of the lever 12. It will be noted that the recess 14 extends over ninety degrees of arc, thereby giving one-quarter 90 turn to the valve at each movement to open the drip-cock or to close it.

The construction described is duplicated for the other cylinder, and the drip-cocks are mounted in any suitable manner. Both ends 100 of the steam-cylinder are opened and closed simultaneously by the action of the lever 12, and the water and steam rush through both outlets in unison. By the use of drip-cocks

or waste-cocks of my invention upon locomotives not only is the engineer enabled to relieve the cylinders of water of condensation, but also to ascertain the condition of the interior packing of the cylinder. For example, if the engineer desires to know if his packing is "blowing," he simply opens the waste-cock and gives the engine steam at either end of the cylinder. If the packing-rings are loose, the steam will leak or blow through to the other end of the cylinder and will issue from both the outlets at once, instantly establishing the fact that the engine should go to the shop for repairs. If, on the contrary, the packing is in good condition, the discharge will be from each outlet alternately. This feature is of the highest importance in railway economy, and the test is as certain and infallible as the devices are simple.

It will of course be noted that by employing two distinctly separate outlets, and especially by arranging them at an angle, the engineer is able to readily detect the condition of the cylinder-packing, as the forward or rearward line of discharge is easily distinguished, whereas in a single outlet common to both, or in the case of two parallel and separate outlets lying side by side, such distinction is rendered almost, if not wholly, impracticable.

I employ no spring to hold the valve to its seat, and thus dispense with a source of constant trouble and uncertainty.

By directing the separate outlets downward and slightly inward the waste or drip cock may be used without danger on lines running through or crossing city streets.

Having thus described my invention, what I claim is—

1. In a drip-cock for locomotive steam-cylinders, the combination, with the drip-pipes leading from opposite ends of said cylinders, of a centrally-located drip-cock having two separate and easily-distinguished outlets and a valve by which communication between both drip-pipes and both outlets may be simultaneously made, substantially as described.

2. In a drip-cock for locomotive steam-cylinders, the combination, with the drip-pipes 50 entering opposite ends of the steam-cylinder, of a drip-cock having two separate and divergent outlets, a valve of slightly-tapering form having a stem passing the bottom of the valve-casing and receiving a draft or set nut and a 55 jam-nut, and means for operating the valve to open the discharge from both ends of the steam-cylinder simultaneously, substantially as described.

3. In a drip-cock for locomotive steam-cylinders, the combination, with the pipes leading from the ends of the steam-cylinder, of a valve having two downwardly-directed outlets, a valve by which both outlets are opened at the same time, and a lever operating the 65 valve and having a stop-pin running in a recess in the valve-casing to control the throw of the lever, substantially as described.

4. In a drip-cock for locomotive steam-cylinders, the combination, with a valve-casing 70 having opposite wings, of pipes tapped into said wings and entering the ends of the steam-cylinder, a tapered valve or plug lying in said casing and having a threaded stem passing through its end, and receiving-nuts, one 75 to set the valve and the other to lock the set-nut, a lever mounted upon the valve and provided with a stop-pin running in a way in the valve-casing, and means for operating said lever, whereby discharge is given to both 80 ends of the steam-cylinder at the same time, the valve-casing being provided with two downwardly-turned diverging outlets, which in one position of the valve register with passages therein communicating at their other 85 ends with the drip-pipes entering the opposite ends of the steam-cylinder, substantially as described.

In testimony whereof I have affixed my signature in presence of two witnesses.

HENRY H. RIGGIN.
